2 SHEETS—SHEET 2.

UNITED STATES PATENT OFFICE.

HAROLD J. KENNARD, OF EASTON, PENNSYLVANIA, ASSIGNOR TO RESEARCH CORPORATION, OF NEW YORK, N. Y., A CORPORATION OF NEW YORK.

APPARATUS FOR THE ELECTRICAL TREATMENT OF GASES.

1,394,771.

Specification of Letters Patent. Patented Oct. 25, 1921.

Application filed May 7, 1918. Serial No. 233,101.

To all whom it may concern:

Be it known that I, HAROLD J. KENNARD, a citizen of the United States, residing at Easton, in the county of Northampton and State of Pennsylvania, have invented certain new and useful Improvements in Apparatus for the Electrical Treatment of Gases, of which the following is a specification.

10 The present invention relates to electrical treatment of gases and especially to apparatus for separating from gases particles suspended therein.

Apparatus of this kind comprise discharge electrodes and collecting electrodes connected, as a rule, to a high voltage direct current supply circuit. As the gas is passed through the space between the discharge electrodes and collecting electrodes, the suspended particles are charged by ions emanating from the discharge electrodes and migrate under the action of this charge toward the collecting electrodes and attach themselves thereto forming a deposit. It is customary to rap the collecting electrodes from time to time to jar the deposit loose and collect it at the bottom of the treater chamber.

It is the object of the present invention 30 to provide a treater, simple in construction and operation and effectively performing the function for which it is intended, which affords means for automatically cleaning the collecting electrodes.

35 It is the more particular object to so construct a treater that its collecting electrodes are continuously kept clean during the operation. The invention to this end consists in the construction and arrangement of parts 40 more fully described in the annexed specification and more particularly defined in the claims.

In the drawings, which forms a part of the specification,

45 Figure 1 is a sectional view taken on line 1—1, Fig. 2;

Fig. 2 is a plan view, the casing being broken away along line 2—2, Fig. 1 and

50 Fig. 3 is a section taken on line 3—3, Fig. 2.

1 represents a substantially cylindrical casing or housing of the precipitator. This casing has on the one side an inlet 2 for the gas to be treated and on the other side an

outlet 3 for the cleaned gas. A shaft 4 extends centrally through the casing 1 and is revolvably mounted in bearings 5 and 6 which are supported upon the frame work 10 of ordinary construction.

On the shaft 4 are mounted a number of 60 disks 7 of electrical conducting material forming the collecting electrodes of the treater. These disks 7 are uniformly spaced from each other to receive centrally between them discharge electrodes. The discharge 65 electrodes may be formed in various ways, but I prefer to use groups of fine wires 8 supported in parallel planes centrally between the disks 7. As particularly shown in Fig. 1, I prefer to use approximately semi-circular bows 9 of electrical conducting material to support the different groups of wires 8 so that two groups are placed between each pair of disks and face each other on opposite sides of the shaft 4. In this 75 manner between each group of discharge electrodes and the adjacent collecting electrodes is produced an electric field which is substantially circular in form, but has a relatively inactive zone near the center to 80 both sides of the shaft 4.

The gas entering through the inlet 2 passes through the passage-ways defined by the disks 7 and is subjected to the action of the electric fields so that the particles suspended in the gas are propelled toward the disks and form a deposit thereon. In the inactive zones mentioned are disposed brush arms 11 in close proximity to the disks 7. These arms, which may be supported on the 85 casing 1 in any suitable manner, bear on the disks to remove the deposit therefrom as the disks are rotated.

The groups of discharge electrode elements are mounted on two separate supports, one on each side of the shaft 4. Each support comprises a bar 12 carried upon insulators 13, a number of forks 14 extending from one side of the bar and a lever 15 extending from the other side of the bar 12 95 and held in fixed relation to the casing by an insulator 16. The bows 9 may be secured to the forks 14 in any suitable manner. The support just described is not essential and may assume other forms, as is obvious. 105

The shaft 4 is driven by a motor 20 through a gear mechanism comprising pinion 21 on the shaft of the motor, gear 24 on the

shaft 4 and gear 22 and pinion 23 on an intermediate shaft 25. The motor and gearing are supported on the frame work 10.

The discharge electrode wires 8 are connected in the well known manner to a high voltage source of current not shown by wires 26 and 27 which pass through an insulator 28 in the casing 1 and make connection with the support 15, 12, 14.

10 The operation is obvious. The gas must pass through the intense electric fields set up between the different groups of discharge electrodes and the collecting electrodes and the particles suspended in the gas are deposited on the latter. During the motion of the disks the wipers or brush arms 11 continuously remove this deposit which falls down into a hopper or hoppers 18 and is removed from time to time through the gates 19 which are normally held closed by weights 19'.

15 It is understood that the detail arrangement may be changed within wide limits within the scope of the invention. The structure disclosed has been merely used as a concrete example to facilitate the understanding of the principle upon which the invention is based.

I claim:—

30 1. Apparatus for the electrical treatment of gases, comprising a revolvably mounted disk-shaped electrode, a stationary filamentary electrode substantially parallel to the side of the disk and means for passing the 35 gas to be treated through the space intermediate the said electrodes.

2. Apparatus for the electrical treatment of gases, comprising a revolvably mounted disk-shaped electrode, a discharge electrode 40 substantially parallel to one side of the disk, means for passing the gas to be treated through the space intermediate the said electrodes and means operative upon the side of the disk to remove deposit therefrom.

45 3. Apparatus for the electrical treatment of gases comprising a revolvably mounted disk-shaped electrode, a discharge electrode at each side of the disk and substantially parallel thereto, means for passing the gas 50 to be treated through the spaces intermediate the disk and the discharge electrodes and means operative upon the disk to remove the deposit therefrom.

55 4. Apparatus for the electrical treatment of gases comprising a plurality of elongated discharge electrodes lying substantially in a single plane, a disk-shaped collecting elec-

trode mounted to revolve in a plane which is parallel to said first plane and spaced therefrom to define a passage for the gas to be 60 treated.

5. Apparatus for the electrical treatment of gases comprising a plurality of elongated discharge electrodes lying substantially in a single plane, a disk-shaped collecting electrode 65 mounted to revolve in a plane which is parallel to said first plane and spaced therefrom to define a passage way for the gas to be treated and means outside said passage way for cleaning the collecting electrode. 70

6. Apparatus for the electrical treatment of gases comprising a plurality of discharge electrodes arranged in groups lying in substantially equidistant parallel planes and a plurality of disk-shaped collecting electrodes 75 mounted in spaced relationship to revolve in planes intermediate the said groups and parallel thereto.

7. Apparatus for the electrical treatment of gases comprising a revolvably mounted 80 disk-shaped collecting electrode, a discharge electrode element spaced from the side of disk to produce an electric field and to define a relatively inactive zone and means in the said inactive zone for cleaning the collecting 85 electrode.

8. Apparatus for the electrical treatment of gases comprising a revolvably mounted shaft, a disk-shaped collecting electrode supported thereon, discharge electrode elements 90 mounted in spaced relation to the collecting electrode on opposite sides of the shaft to produce two electric fields separated by a relatively inactive zone adjacent the shaft, and means in said inactive zone having frictional engagement with the side of the collecting electrode. 95

9. Apparatus for the electrical treatment of gases comprising a disk mounted to revolve in a substantially vertical plane, means 100 for producing adjacent the side of said disk a field of electric stress and a relatively inactive zone, and means in said inactive zone for cleaning the disk.

10. Apparatus for the electrical treatment 105 of gases comprising a revolvably mounted disk, means for producing adjacent the side of said disk a field of electric stress and a relatively inactive zone, means in said inactive zone for cleaning the disk and means 110 for causing the gas to pass through said field in planes parallel to the disk.

In testimony whereof I affix my signature.
HAROLD J. KENNARD.
